United States Patent Office

Des. 203,085
Patented Nov. 30, 1965

203,085

AIRCRAFT

Lawrence Bernard Rellis, San Diego, Calif.
(734 NW. 80th St., Miami, Fla.)

Filed Sept. 1, 1964, Ser. No. 81,547

Term of patent 3½ years

(Cl. D71—1)

EJ-2

EJ-3

FIG. 1 is a perspective view of the aircraft, with flaps in the operating position, showing my new design.

FIG. 2 is a side elevational view; the opposite side is shown in the perspective view, FIG. 1;

FIG. 3 is a top plan view thereof;

FIG. 4 is a bottom plan view thereof with the vertical lift turbine engines shown in the wing members;

FIG. 5 is a front elevational view thereof with the wheels in lowered position;

FIG. 6 is a rear elevational view thereof.

I claim:

The ornamental design for an aircraft, as shown and described.
